"Church & Church
MS. A. 1. 1145.

UNITED STATES PATENT OFFICE.

GEORGE E. ADAMS, OF NEW BRITAIN, CONNECTICUT.

DESIGN FOR A METALLIC LOOP FOR GARMENT-SUPPORTERS.

SPECIFICATION forming part of Design No. 33,636, dated December 4, 1900.

Application filed November 3, 1900. Serial No. 35,424. Term of patent 7 years.

To all whom it may concern:

Be it known that I, GEORGE E. ADAMS, a citizen of the United States, residing at New Britain, in the county of Hartford, State of Connecticut, have invented and produced a new and original Design for a Metallic Loop for Garment-Supporters, of which the following is a specification, reference being had to the accompanying drawings, forming part thereof.

Figure 1 is a face view of a metallic loop, showing my new design. Fig. 2 is a top plan view of the same.

As shown in the drawings, the leading or material feature of my design consists of two loops—one, A, elongated transversely and

having its central portion B extending downwardly, and the other, C, being curved and terminating in edge flanges c, while its upper portion D is circular and merges into the downwardly-extending portion B of the upper loop A. The circular portion D has a central opening E, surrounded by a bead F. 20

I claim—

The design for a metallic loop of a garment-supporter as herein shown and described.

GEORGE E. ADAMS.
